CLAIM

The ornamental design for a wearable tracking device with dimpled end cap, as shown and described.

DESCRIPTION

FIG. 1 is a perspective view of an illustrative wearable tracking device with dimpled end cap taken from the top, right, and front in a representative environment, and illustrating a first orientation;

FIG. 2 is another perspective view of the wearable tracking device with dimpled end cap taken from the top, right, and front in isolation, and showing the wearable tracking device as it appears with the end cap disconnected from the body of the wearable tracking device;

FIG. 3 is another perspective view of the wearable tracking device with dimpled end cap taken from the top, left, and back in the representative environment, and illustrating a second orientation;

FIG. 4 is another perspective view of the wearable tracking device with dimpled end cap taken from the top, left, and back in isolation, and showing the wearable tracking device with dimpled end cap as it appears with the end cap disconnected from the body of the wearable tracking device with dimpled end cap;

FIG. 5 is a front elevation view of the wearable tracking device with dimpled end cap of FIG. 1 in isolation;

FIG. 6 is a back elevation view of the wearable tracking device with dimpled end cap of FIG. 1 in isolation;

FIG. 7 is a right side elevation view of the wearable tracking device with dimpled end cap of FIG. 1 in isolation;

FIG. 8 is a left side elevation view of wearable tracking device with dimpled end cap of FIG. 1 in isolation;

FIG. 9 is a top plan view of the wearable tracking device with dimpled end cap of FIG. 1 in isolation; and,

FIG. 10 is a bottom plan view of the wearable tracking device with dimpled end cap of FIG. 1 in isolation.

The broken lines shown in the drawings are directed to environment or illustrate portions of the wearable tracking device with dimpled end cap that form no part of the claimed design.
